UNITED STATES PATENT OFFICE.

ALEXANDER F. JENKINS, OF BALTIMORE, MARYLAND.

ACETYLENE GENERATOR.

Application filed June 27, 1921. Serial No. 480,708.

To all whom it may concern:

Be it known that I, ALEXANDER F. JENKINS, a citizen of the United States, and residing at Baltimore city, State of Maryland, have invented certain new and useful Improvements in Acetylene Generators, of which the following is a specification.

The present invention relates to acetylene gas generating units and particularly to apparatus of this class for generating such gas in large volumes and under relatively high pressures.

Factories, work shops, public buildings, and hotels frequently are provided with apparatus for generating acetylene gas for lighting purposes or for use in metal cutting and welding operations. In some instances it is unnecessary to provide a gas under any appreciable pressure, but for other purposes a pressure of from 10 to 15 pounds per square inch is desirable. So far as possible these generating units, whether installed singly or in multiple, and connected to form a battery, are arranged to operate automatically so as to render unnecessary the constant attendance of an operator to properly feed the carbide and water to the tank. Automatically operating water and carbide feeding devices have heretofore been devised or suggested and it is the object of the present invention to provide a gas generator of this character having not only automatic carbide and water feeding devices, but also an automatic sludge removing mechanism whereby waste water and sludge is automatically removed, so that it will run long periods of time without attendance. The sludge removing device is of such character that the pressure desired within the tank is not lowered below the desired minimum due to its operation.

The invention may be embodied in various forms, one of which is illustrated in the accompanying drawings. In the drawings:

Fig. 1 is a side elevation of an acetylene gas generating tank, parts being broken away to illustrate the application of the present invention thereto;

Fig. 2 is a side elevation of the lower portion of the tank taken at right angles to Figure 1 and partly broken away; and

Fig. 3 is a section on line 3—3 of Figure 1.

The generator comprises a metallic tank 10 of generally cylindrical form having an opening in its top for the introduction of

carbide which opening is normally closed by a cap 11, and having an upwardly flaring conical bottom 12 which acts as a funnel in collecting the sludge, and guiding it toward the central opening 12^a therein. The carbide introduced through the opening in the top of the tank may be fed downwardly by any well known carbide feeding mechanism, preferably by that disclosed in the copending application of A. F. Jenkins, Ser. No. 347,719 filed Dec. 27, 1919. In this case it rests in a hopper 13 having a slotted bottom located immediately above the rotatable cylindrical drum 14, indicated in dotted lines in Figure 1, this drum being fixed on a rotatable shaft 15 which is connected by reducing gearing R to the shaft 16 of a rotary water motor 17. A pipe 18 is provided for conducting water under pressure from a city main or other suitable source to the motor 17 and a pipe 19 conducts the water exhausted from the motor to the interior of tank 10. This pipe enters tank 10 in such manner that the jet of water issuing thereinto is substantially tangential to the wall of the tank so that the water in the tank is in constant movement, flowing slowly in a circular path about the vertical axis of the tank.

An additional supply pipe 20 for water under pressure enters tank 10 substantially radially and has a lateral outlet 21 so that the jet which enters the tank through this orifice is tangential to its wall and assists which enters through pipe 19 in maintaining the swirling motion of the body of water. Passage of water through pipe 20 is controlled by a valve operated by a float 22 in such manner that the water is maintained substantially at the level at which it is shown in Figure 2 at all times. Connected to the funnel shaped bottom below opening 13 is a valve casing 23 which houses a large gate valve adapted to be manually opened to permit the escape therethrough of water and sludge. Below this valve is a double piston rotary gear pump 24, one piston of which is mounted on a shaft 25 which is connected to the shaft 16 of the water motor by a belt 26 and the reducing gearing R. This rotary gear pump is of the well-known type in which the pumping action is obtained by the rotation of a plurality of intermeshing gears, fitted within a casing provided with inlet and outlet ports. The outflow of water and sludge from

the bottom of the tank is positively controlled by pump 24 and this pump is so geared to the motor 17 as to operate at such speed that it will remove water from the tank faster than water flows into the tank through pipe 19. To maintain the water level constantly therefore a considerable quantity is supplied through pipe 20, the float 22 controlling the actual flow of water 10 through this pipe.

The escape of gas from tank 10 is so governed by reducing valves or similar devices not illustrated, that the pressure existing in the tank is the exact pressure desired 15 to accomplish the particular purpose for which the gas is being used.

The pump is substantially leakproof, being water sealed and having quantities of sludge continuously passing therethrough so 20 that the pressure above it can not force the water from the tank through the pump to allow the escape of gas through the waste pipe 27.

The design and arrangement of the component parts of the invention may be considerably varied by one skilled in the art 25

and the invention is not limited in its scope to the exact embodiment shown and described.

What is claimed as new and desired to be secured by Letters Patent is:

1. In a gas generating apparatus of the class described, in combination, a gas generating tank, a conduit for leading water under pressure to said tank, a water motor operated by the water passing through said conduit, and a pump for continuously removing sludge and waste water driven from the motor.

2. In a gas generating apparatus of the class described, in combination, a tank, means for removing water from the tank at a uniform rate and means for supplying the tank with fresh water including a constantly open inlet conduit, a second inlet conduit, a valve governing the flow through said second conduit and means for automatically opening said valve when the water in the tank falls below a predetermined level.

In testimony whereof I hereunto affix my signature.

ALEXANDER F. JENKINS.
